UNITED STATES PATENT OFFICE.

ALLAN A. ADAMSON, OF ROCHESTER, NEW YORK, ASSIGNOR TO GEORGE H. HARRIS,
OF ROCHESTER, NEW YORK.

CIGAR BOX.

Application filed January 31, 1925. Serial No. 5,021.

The present invention relates to cigar boxes and more particularly to the type made of wood, paper board or a combination of the two and having a hinged cover or lid and 5 end walls projecting vertically above its front and rear walls. An object of this invention is to provide edging for a box of this type which will permit the cost of manufacture of the box to be reduced. A further object of this invention is to combine the edging with labels so that the operations in the manufacture of the box will be reduced.

To these and other ends, the invention consists of certain parts and combinations of 10 parts, all of which will be hereinafter described: the novel features being pointed out in the appended claims.

In the drawings:

Fig. 1 is a front perspective view of a box 20 constructed in accordance with this invention, the lid or cover of the box being broken away;

Fig. 2 is a fragmentary rear perspective view;

Fig. 3 is a plan view of one of the blanks 25 for edging and labeling the front and end walls of the box body;

Fig. 4 is a plan view of another blank for edging the rear wall and a portion of the lid 30 or cover;

Fig. 5 is a rear view of the body before the rear edging section is applied thereto;

Fig. 6 is a plan view of the cover label and edging; and

Fig. 7 is a rear view of the lid or cover 35 after the cover edging and label has been applied.

Referring more particularly to the drawings, 1 indicates the bottom of the box having a front wall 2, a rear wall 3, and end walls 4 projected above the front wall and rear wall. A cover member 5 is hingedly secured to the rear wall 3 by a hinging strip 6. The cover, in this instance, embodies a combined label and edging such as shown in Fig. 6, and will not be described in detail herein as it forms the subject matter of an application filed by me on even date herewith. This cover is edged and labeled independent- 50 ly of the box body and is applied to the box body after the blank shown in Fig. 3 has been applied, and before the blank shown in Fig. 4 is applied. The cover before being applied to the box body with the combined edging and labeling thereon has the appear-

ance from the top side like Fig. 6 of the drawings, its rear edge being exposed so that the hinging tape 6 may be adhesively secured directly to the material of the cover. The edging for the box embodies, in this instance, 60 two distinct blanks, one being illustrated in Fig. 3 and the other being illustrated in Fig. 4.

The blank illustrated in Fig. 3 consists of a central section 7 for the front wall, and 65 two end sections 8 for the end walls foldable on lines 9 to provide the different sections. The central section 7 which is placed on the front of the box has a bottom tongue 10 foldable on the line 11 and forms with the 70 lower portion of the section 7 the edging for the lower horizontal corner, this tongue being bent and adhesively secured to the underside of the bottom wall 1. This central section also has a tongue 12 foldable on the 75 lines 13 and 14 and of less length than the tongue 10. This tongue 12 folds over the upper edge and down on the inner side of the front wall and forms on the adjacent portion of the section 7 the edging for the 80 upper front edge of the box. Between the ends of the tongue 12 and the adjacent fold lines 9, the front wall has extensions 15 which cover the front ends of the end walls 4 above the upper edge of the front wall, 85 due to the fact that the end walls extend above said front wall. The section 7 has a central opening 16 which exposes the front face of the vertical front wall 2. The end sections 8 are, in this instance, identical and each 90 has at its lower edge a tongue 17 foldable on the line 18 to extend over the underside of the bottom wall 1. Each end section 8 also has a tongue 19 foldable on the lines 20 and 21. The distance between the fold line 21 95 and the fold line 18 being greater than the distance between the fold line 11 and the fold line 14 of the section 7 due to the fact that the end walls are of greater height than the front wall. The tongues 19 are notched at opposite ends to provide shoulders 22, the distance between which and the fold line 20 being equal to the difference between the heights of the end walls and the front and rear walls.

The blank of Fig. 3 is first applied to the box body so that it covers the front wall of the two end walls, the end flaps 23 on the end section 8 being then bent over the rear wall. Thereafter the cover formed as 110

shown in Fig. 6 is secured to the rear wall through the hinging tape 6 and the rear wall of the box will then have the appearance shown in Fig. 5.

7 The rear section 24 is now applied to the box. This section has a lower flange 25 foldable on the line 26 to extend over the bottom of the box. It also has a tongue 27 foldable on the lines 28 and 29, the line 29 10 being coincident with the hinging line of the box and the line 28 being coincident with the rear corner of the cover of the box, the portion beyond the line 28 extending over the cover of the box and forming the edging for the rear edge of the latter. The tongue 27 is shorter than the tongue 25 and beyond the ends of the tongue the section 24 has extensions 30, the lengths of 15 which are equal to the difference in height 20 between the rear wall and the end walls, so as to cover the portions of the end walls projecting beyond the rear wall. After this section is secured in place the edging of the box is complete.

25 It will be noted that the blanks herein shown provide for edging and labeling the box by automatic machinery with comparatively few operations. An edging blank is provided having three sections for 30 the front and end walls of the box leaving the rear wall exposed for the attachment of the cover or lid. The rear section is separate from the other section and is applied after the cover is secured in place so 35 that a portion thereof may be used as an edging for the rear face of the cover or lid while, at the same time, covering the hinging 40 strip of the cover.

What I claim as my invention and desire 45 to secure by Letters Patent is:

1. In combination with a cigar box having a hinged cover and end walls projecting above the front and rear walls of the box, an edging blank having at least three 45 sections, all of said sections having tongues at one and the same edge extending onto the bottom of the box, two of said sections having tongues formed with shoulders at

their opposite ends and extending over the upper edges of the end walls and downwardly onto the inner faces of said end walls, and the intermediate section having a tongue shorter than the tongue on the opposite edge of said section and extending over the upper edge of the front wall and downwardly on the inner face of the front wall, said intermediate section having extensions beyond said tongue covering those edge portions of the end walls projecting above the front wall, and a separate blank 60 forming the edging for the rear wall and having a tongue at its lower edge extending onto the bottom wall and a tongue at its upper edge shorter than the tongue on such bottom wall, extending onto the hinged cover, said other blank having extensions at opposite ends of the shorter tongue, covering those portions of the edges of the end walls projecting above the rear wall.

2. A cigar box comprising a body having 70 end walls projecting above its front and rear walls, a cover hinged to the rear wall, an edging blank having three sections, the two end sections of said blank having portions extending onto the bottom of the bottom wall and portions extending over the top edge of the end wall and down on the inner face of such end wall, an intermediate section on the front wall having a portion 75 extending onto the bottom wall, and a portion 80 extending over the upper edge of the front wall and down on the inner side of said front wall, and a separate edging on the rear wall having a portion extending onto the bottom wall and a portion extending 85 onto the top face of the rear edge of the cover of the box.

3. In combination with a cigar box having a hinged cover, an edging blank having 90 portions edging the lower horizontal corners of the front and end walls and the upper edges of the front and end walls, and a separate blank edging the rear wall, the lower horizontal corner of the bottom wall and the rear outer face of the cover.

ALLAN A. ADAMSON.
